Allen S. Hatcher

UNITED STATES PATENT OFFICE

108,393

DESIGN FOR A TEXTILE FABRIC

Allen S. Hatcher, Mount Holly, N. J.

Application January 12, 1938, Serial No. 74,229

Term of patent 3½ years

To all whom it may concern:

Be it known that I, Allen S. Hatcher, a citizen of the United States of America, residing in the city of Mount Holly, State of New Jersey, have invented a new, original, and ornamental Design for a Textile Fabric of which the following is a specification, reference being had to the accompanying drawing, forming part thereof, wherein:

The figure is a plan view of a piece of textile fabric showing my new design.

I claim:

The ornamental design for a textile fabric substantially as shown.

ALLEN S. HATCHER.
